UNITED STATES PATENT OFFICE.

STEPHEN NOGRADY, OF CHICAGO, ILLINOIS.

WRENCH.

1,233,694.

Specification of Letters Patent. Patented July 17, 1917.

Application filed November 7, 1916. Serial No. 130,012.

To all whom it may concern:

Be it known that I, STEPHEN NOGRADY, a subject of the King of Hungary, residing at Chicago, in the county of Cook and State of Illinois, have invented certain new and useful Improvements in Wrenches, of which the following is a specification.

This invention relates to new and useful improvements in wrenches.

10 An object of the invention is to provide a wrench which embodies a fixed outer jaw and a spring pressed inner jaw, the inner jaw being normally forced outwardly and having associated therewith a shank 15 threaded over a portion of its side whereby when moved to the desired position the threads thereof may be disengaged from threads upon the movable inner jaw whereby the spring therefor may force the inner 20 jaw outwardly into gripping engagement with an object, and at which time the said threaded shank may be rotated to cause the threads thereof to engage threads on the movable jaw to lock the same in adjusted 25 position.

A further object of the invention is to provide a wrench of the type above set forth that is entirely automatic in its operation, *i. e.*, the constant tension upon the 30 inner jaw and the return to operative position of the threaded shank to engagement with the threaded inner jaw.

With these general objects in view and others that will appear as the nature of the 35 invention is better understood, the same consists in the novel combination and arrangement of parts hereinafter fully described, illustrated in the accompanying drawing and then claimed.

40 In the drawing forming a part of this application and in which like designating characters refer to corresponding parts throughout the several views:—

Figure 1 is a side elevational view, partly 45 in section and with portions removed of a wrench constructed in accordance with the present invention.

Fig. 2 is a rear elevational view thereof.

Fig. 3 is a cross sectional view taken on 50 line III—III of Fig. 1 showing the manner of retaining the locking threaded shank in position in the wrench.

Fig. 4 is a cross sectional view taken on line IV—IV of Fig. 1 showing the locking 55 connection between the threaded shank and the inner face of the inner movable jaw.

Fig. 5 is a similar view with the locking threaded shank partially rotated to disengaged position from the jaw.

Fig. 6 is a cross sectional view taken on 60 line VI—VI of Fig. 1, showing the manner of placing the threaded shank under tension, and

Fig. 7 is a detail perspective view of the inner end of the locking threaded shank. 65

Referring more in detail to the accompanying drawing, the reference numeral 10 designates the frame or body portion of the wrench which is of U-shape in cross section, as clearly shown in Figs. 4 and 5, a 70 fixed jaw 11 being carried by the outer end thereof while a bolt 12 projects from the inner end for the reception of a handle 13 retained in position by the end cap 14 as shown in Figs. 1 and 2. 75

A sliding inner jaw 15 having a rectangular opening through the main body portion thereof is slidably mounted on the U-shaped frame 10, the inner jaw including a rearwardly projecting portion 16 having an 80 opening therein through which projects a rod 17 arranged parallel to the frame 10, the said rod having threaded engagement at its outer end as at 18 with the outer fixed jaw 11 while the inner end thereof projects 85 through a rearward extension 19 upon the frame 10, the inner end of the rod 17 including a slotted head 20 by which the said rod may be threaded into the outer jaw 11. An expansion coil spring 21 surrounds the 90 rod 17 intermediate the rearward extension 16 upon the inner jaw and the extension 19 upon the frame 10 so that the inner jaw 15 is at all times spring-pressed outwardly. 95

Means is provided for holding the inner 100 jaw 15 in adjusted position and includes a shank 22 having corrugations or threads 23 formed upon a single longitudinal side face thereof as is clearly shown in Figs. 4 to 7, the outer end thereof being reduced as at 24 to be journaled in the outer fixed jaw 11 and retained in such position by the set screw 25 which engages the same in such manner as to permit a free rotation thereof. The inner end of the shank 22 is reduced as at 105 26 and is adapted to be journaled in portions 27 of the frame 10. A coil spring 28 surrounds the reduced portion 26 and has one end connected thereto as at 29 while the other end is engaged in the frame 10 as indicated at 30. The inner face of the inner movable jaw 15 has one side thereof pro-

vided with rack teeth or threads 31 that are adapted to be normally engaged by the threads 23 upon the shank 22, this connection being effected by the spring 28 normally holding the threads in engagement. As shown in Fig. 6, a removable cover plate 33 is provided for the lower end of the wrench frame 10 which will house the shank operating spring 28 to protect the same from 10 injury.

When it is desired to disconnect the inter-engaging threads, for purposes of adjusting the jaw 15, the shank 22 may be partially rotated against the tension of the 15 spring 28 by engagement with the finger grip 32 to rotate the shank so that the threads are disengaged and at which time the spring 21 will force the jaw 15 outwardly into engagement with the member A. 20 When the jaw 15 so engages the member A, pressure on the finger grip 32 may be released and the spring 28 will rotate the shank 22 so that the threads 23 thereof engage the threads 31 upon the movable jaw 25 to retain the same in adjusted position.

What I claim as new is:—

In a device of the class described com-

prising a wrench frame U-shaped in cross section, a jaw fixed to the outer end thereof, a handle carried by the inner end of said frame, rearward extensions upon said frame and outer jaw, a rod passed through said frame extension and threaded into said jaw extension, a sliding inner jaw mounted on said U-shaped frame and rod, an expansion 35 coil spring surrounding said rod between the frame extension and the inner movable jaw, a shank having threads on one side face thereof journaled at its outer end in said outer fixed jaw and at its inner end 40 in said jaw frame, threads upon one side face of said inner jaw adapted to be engaged by the threads on said shank, a coil spring surrounding the inner end of said threaded shank, connected at one of its ends 45 to said shank and at its other end to said jaw frame whereby the threaded shank is normally held in position whereby the threads thereof engage the threads of the inner jaw, and means for moving the shank 50 against the tension of the spring to disconnect the engaging threads.

In testimony whereof I affix my signature.
STEPHEN NOGRADY.

Copies of this patent may be obtained for five cents each, by addressing the "Commissioner of Patents, Washington, D. C."
